UNITED STATES PATENT OFFICE.

RICHARD C. MCKILIGET, OF NEW ORLEANS, LOUISIANA.

CABLE OR WIRE HANGER.

No. 825,236.

Specification of Letters Patent.

Patented July 3, 1906.

Application filed September 27, 1905. Serial No. 280,371.

To all whom it may concern:

Be it known that I, RICHARD C. MCKILIGET, a citizen of the United States, residing at New Orleans, in the parish of Orleans and 5 State of Louisiana, have invented certain new and useful Improvements in Cable or Wire Hangers; and I do hereby declare the following to be a full, clear, and exact description of the invention, such as will enable 10 others skilled in the art to which it appertains to make and use the same.

This invention relates to improvements in wire or cable hangers and is especially applicable for suspending the feed-wire of an 15 overhead-trolley line.

The principal object of the invention is to provide a simple, cheap, and effective means for replacing a worn or broken hanger-support by a new one with comparatively little 20 labor and loss of time.

With this object in view the broad idea consists in suspending the shoe member proper by a pair of opposed hangers adapted to be folded upon and interlocked with a 25 rigid hanger member carried by the pole or other support, the grooved or channeled portion of the shoe member being of suitable resilient metal to act as a hinge for said movable hanger members.

30 In the specification and claims the term "fixed" is employed to distinguish that portion of the suspension means which is adapted to be fixed to the pole or other support from the "movable" hanger members, which 35 are adapted to be detachably connected to said fixed member.

The following is a detailed description of the invention, the particular features of novelty being pointed out in the claims, and to 40 more clearly understand the invention reference is had to the accompanying drawings, illustrating an application of the same, in which like figures designate the same parts in the several views, and in which—

45 Figure 1 is a side elevation of one of my improved hangers with a trolley-wire suspended thereby. Fig. 2 is an end elevation of same. Fig. 3 is an end view in detail of the shoe member and movable hangers suspending 50 same, the dotted lines showing said hangers in their partially open position when the same is to be secured or released from the trolley-wire; and Fig. 4 is a view in elevation of the coöperating fixed hanger member.

55 1 is the cable or trolley-wire; 2, the elong-

gated grip or shoe member therefor, comprising two side pieces of rigid material provided with inwardly-disposed engaging shoulders 2^a and connected by the longitudinal strip 2^b of resilient metal, the parts being so 60 associated with a pair of opposed hanger or hinged members 3 and 4 as to provide a hinge connection between said members. The object of the engaging shoulders 2^a, as is clearly seen from the drawings, is to prevent the 65 wire or cable from rising between the spaced members of the shoe when the parts are clamped into position. In the drawings this is illustrated by the side pieces of the shoe being affixed to the hanger members 3 and 4, 70 the metallic strap 2^b, longitudinally connecting the lower edges of the side pieces, being of sufficient flexibility or resiliency to operate as a hinge.

The hanger members 3 and 4 are of segmental contour, externally screw-threaded 75 and adapted to receive between them a similarly screw-threaded tongue 5, forming a portion of the hanger or support adapted to be fixed to the pole or other main support. In 80 order to make a more perfect connection between the members 3, 4, and 5, the member 3 is of less length than the member 4, the difference in length being compensated for by the non-cut-away screw-threaded portion of 85 the fixed hanger member, (designated by the numeral 6,) the end faces of the members 3 and 4 when the parts are assembled in position being adapted to rest snugly against the shoulders 6^a 6^b, respectively, formed by the 90 tongue 5 and enlarged portion 6.

The fixed hanger member is preferably provided with a base-piece 7 and may be connected to the pole or other support in any suitable way. In the drawings this is illustrated by providing the member with an internally-screw-threaded socket 7^a, adapted to engage a screw-threaded plug on the pole or support.

8 and 9 are a pair of nuts for interlocking 100 the fixed tongue and movable hanger members in their assembled position.

From the foregoing description, in connection with the illustrative drawings, the operation of the device is apparent.

105 It will be understood, however, that while the drawings and the description disclose a practical application of the invention I do not restrict myself to the exact details illustrated and described, as it is obvious that 110

modifications might be made without departing from the spirit of the invention.

What I claim is—

1. The combination with a fixed hanger member, of a shoe comprising spaced members, one of said members being provided with an inwardly-disposed shoulder adapted to engage the upper portion of a suspended wire or cable, a pair of movable hanger members suspending said shoe, and means for interlocking said movable members to said fixed member, substantially as described.
2. The combination with a fixed hanger member, of a pair of movable members coöperatively associated therewith, a shoe member composed of two sections suspended by said movable members, means resiliently connecting the lower portion of said sections and forming a seat for a suspended wire or cable, and means for interlocking said movable members and fixed member when assembled, substantially as described.
3. The combination with a fixed hanger member comprising a bolt cut away to form a projecting tongue portion and shoulders, of a shoe, a pair of movable hanger members suspending said shoe, said movable members being externally screw-threaded and of segmental conformation with respect to said fixed hanger and adapted to snugly engage the tongue and shoulders of said fixed member and form therewith a separable bolt, and a nut for interlocking said members when assembled, substantially as described.
4. The combination of a fixed hanger member comprising a bolt cut away to form

a projecting tongue portion and non-aligned shoulders, a shoe member, a pair of movable hanger members suspending said shoe member, said movable members being externally screw-threaded and of segmental conformation, and one of said movable members being of less length than the other, said movable members and the ends thereof being adapted to snugly engage the tongue and shoulders of said fixed member and form therewith a separable bolt, and a nut for interlocking said members when assembled.

5. The combination with the fixed hanger member provided with the screw-threaded tongue portion, of externally-screw-threaded movable hanger members coöperatively associated with said fixed hanger member to form therewith a separable bolt, an interlocking nut for said members when assembled, and a shoe member suspended by said movable hanger members, comprising a pair of elongated side pieces secured to said movable hanger members, engaging shoulders formed on the lower edges of said side pieces, and a strap of flexible metal extending longitudinally of the lower edges of said side pieces, secured thereto and forming with said shoulders a gripping means for the cable or wire when the parts are assembled and interlocked.

In testimony whereof I affix my signature in presence of two witnesses.

RICHARD C. MCKILIGET.
